DESIGN FOR A BABY ROCKER

Clifford I. Sweet, Delphos, Ohio, assignor to The Delphos Bending Company, Delphos, Ohio, a corporation of Ohio

Application September 17, 1934, Serial No. 53,314

Term of patent 14 years

To all whom it may concern:

Be it known that I, CLIFFORD I. SWEET, a citizen of the United States, residing at Delphos, Van Wert County, Ohio, have invented a new, original, and ornamental Design for a Baby Rocker, of which the following is a specification, reference being had to the accompanying drawing, forming part thereof.

The single figure of the drawing is a perspective view of a baby rocker embodying my new design.

I claim:

The ornamental design for a baby rocker, as shown.
